TO WESTERN ELECTRIC COMPANY, INCORPORATED, A CORPORATION OF NEW YORK.

SELECTING MECHANISM.

1,212,531.

Specification of Letters Patent. Patented Jan. 16, 1917.

Application filed February 26, 1915. Serial No. 10,673.

To all whom it may concern:

Be it known that I, FRED R. McMURRY, a citizen of the United States, residing at Westwood, in the county of Bergen and State of New Jersey, have invented certain new and useful Improvements in Selecting Mechanisms, of which the following is a full, clear, concise, and exact description.

This invention relates to selecting mechanisms and one of its principal objects is to provide such a mechanism wherein the necessity for wiping contacts between insulated segmental structures and current collecting or distributing devices is obviated.

15 A further object is to provide a selecting mechanism employing a single electromechanical system which may be used interchangeably as an impulse transmitter, receiver, or transmitter and receiver.

20 To the above ends, the invention contemplates the use of an electrically actuated switch controller, such as a cam or cams, so constructed and arranged that it affects the associated switches successively to transmit 25 a succession of current impulses or to distribute the effects of such impulses or to do both simultaneously.

The above and other objects of this invention will be fully set forth in the following 30 description and claims, and will be more readily understood by reference to the accompanying drawing, in which—

Figure 1 shows the apparatus and circuit connections in diagrammatic form; and Fig. 35 2 is a detail of one of the cams and its associated switch contact springs.

The switches 5, 6, 7, 8, 9, 15, 16, 17, 18 and 19 are insulatively secured to any desired form of support and may be considered as 40 divided into two sets. One contact spring of each of the switches 5, 6, 7, 8 and 9, comprising one set, is connected to a front contact 20 of a relay 21, while the coöperating contact springs of the corresponding switches 45 are grounded through the windings 25, 26, 27, 28 and 29 respectively of an electromechanism, such, for example, as the type selecting mechanism of a printing telegraph instrument. The other set is composed of switches 15, 16, 17, 18 and 19 which have one of their contact springs connected 50 to pole changers 35, 36, 37, 38 and 39 respectively, while the coöperating contact springs are connected to a fixed contact 45 of a line switch 46. Pole changers 35 to 39 inclusive,

by means of suitable circuit connections, are adapted to join either terminal of a grounded source of energy 47 to the corresponding contact springs of switches 15 to 19 inclusive. Line switch 46 comprises besides the 60 fixed contact 45, a movable contact 48 and a second fixed contact 49. The pole changers 35 to 39 inclusive, forming a suitable current controlling means, may be selectively controlled by any suitable apparatus, 65 as for example, selecting keys arranged in the form of an ordinary typewriter keyboard, or in an automatic mechanism controlled by a perforated tape or the like.

The switches 5 to 9 inclusive and 15 to 19 inclusive are operated by a plurality of cams 55 to 59 inclusive and 65 to 69 inclusive mounted to rotate upon a cam shaft 70. These cams may be mounted separately, as shown, or as a unitary structure, and each 75 may be provided with projections, such as the teeth 75 shown in Fig. 2. These teeth are adapted to engage one of the contact springs of the corresponding switch and are so positioned with respect to those on the 80 other cams that the switches are successively actuated in pairs as the shaft 70 rotates. Thus, switches 5 and 15 are operated simultaneously, next switches 6 and 16, and so on until the last pair 9 and 19 are closed and 85 then opened, completing one cycle of operations in the particular system disclosed. It is, however, to be understood that the number of switches and the number and grouping of the sets thereof may be altered without departing from the spirit of the invention.

In the particular mechanism disclosed, each cam is provided with three teeth 75, which means that only one-third of a revolution is necessary for each cycle. This, however, of course may be changed to suit any condition. Shaft 70 is provided with suitable bearings and a ratchet wheel 76 having a sufficient number of teeth so positioned as to insure the successive closing and opening of each pair of switches in the manner hereinbefore described. In the normal condition of the apparatus, the teeth of cams 55 and 65 respectively hold the switches 90 5 and 15 closed as shown.

The teeth of the ratchet wheel 76 are engaged by a pair of actuating pawls 80 and 81 pivoted to a suitable rocking frame 82 at 100 83 and 84 respectively. A spring 85 interconnects 105

pawls 80 and 81 and holds them against the teeth of the ratchet wheel. Rocking frame 82 is pivoted at 86 to a lever 87 and at 90 to an armature lever 91. Armature lever 91 is operated in one direction by the attractive force of an electromagnet 92 and in the other direction by a retractile spring 93. A pair of stops 95 and 96 coöperate with projections 97 and 98, which extend from the pawls 80 and 81, to limit the extent of each step and to positively hold the cam shaft 70 in position between each step.

The winding of electromagnet 92 is connected to a grounded source of energy 93 and to a front contact 106 of relay 21 and a front contact 101 of relay 102. The windings of relays 21 and 102 are connected in multiple directly to the fixed contact 49 of line switch 46 and through a resistance 105 to the main line L and movable contact 48 of line switch 46. The other terminals of the windings of relays 21 and 102 are connected to ground and to their armatures 107 and 108 respectively. Armature 109 of relay 21 is connected to a grounded source of energy 110. Relays 21 and 102 are polarized, in the specific embodiment shown, relay 21 being responsive only to positive currents while relay 102 is responsive to negative currents only. Resistance 105 is preferably so proportioned that its resistance plus the resistance of the parallel path to ground through the winding of relays 21 and 102 is equal to the resistance of line L and the apparatus connected therein at the distant station.

The operation of the selecting mechanism when used as a combined impulse transmitter and effect distributor is as follows: The manipulation of the apparatus for controlling the pole changers 35 to 39 inclusive, in addition to selectively transferring certain of the movable parts of these members from the right to the left-hand contact, likewise shifts movable contact 48 of line switch 46 from fixed contact 49 to fixed contact 45. Assuming that pole changer 35 has been shifted, there is a flow of positive current from source 47 through pole changer 35 and switch 15, contacts 45 and 48 of line switch 46, and in parallel through line L and the resistance 105 and the windings of relays 21 and 102. Relay 21 being positively polarized, pulls up its armatures 107 and 109. Armature 109 engages front contact 20, connecting battery 110 through winding 25 to ground, while armature 107, engaging front contact 106, completes a path for grounded source of energy 93 through electromagnet 92, which thereupon attracts its armature lever 91. The movement of armature lever 91 causes pawl 81 to engage a tooth of ratchet wheel 76, advancing the cam shaft 70 one step. This step moves the cam wheels 55 and 65 until their teeth 75 no longer engage

one of the contact springs of switches 5 and 15, whereupon the switches are opened, breaking the previously traced circuits including pole changer 35 and winding 25. The opening of switch 15 terminates the first impulse over line L and through relays 21 and 102, causing the previously energized relay 21 to release its armatures 107 and 109. The release of armature 109 opens the circuit from battery 110 to its set of switches, while the release of armature 107 breaks the circuit for electromagnet 92. The deenergization of electromagnet 92 allows spring 93 to return armature lever 91, causing pawl 80 to engage a tooth of ratchet wheel 76, giving the cam shaft 70 a second step. This step causes the teeth 75 of cams 56 and 66 to close switches 6 and 16. The closing of switch 16 initiates the second impulse from battery 47 through pole changer 36 to line L and the polarized relays 21 and 102, while the closing of switch 6 partially prepares a circuit for the winding 26 which will be completed through battery 110, provided this second impulse is of positive polarity to cause the energization of relay 21. If, however, the position of pole changer 36 has not been altered from its right-hand to its left-hand contact, a negative impulse will be transmitted to line L and the polarized relays 21 and 102, causing the energization of negatively polarized relay 102. This condition merely causes the shaft 70 to take two steps, one upon the energization of electromagnet 92 and the other upon the deenergization of this magnet. The deenergization of the magnet marks the beginning of the third impulse which is controlled by pole changer 37. The third energization of the electromagnet 92 terminates the third impulse, and the third deenergization initiates the fourth impulse controlled by pole changer 38. The fourth deenergization of the electromagnet completes the cycle of operation and switches 5 and 15 are again closed for the beginning of the next selection. Where the pole changers 35 to 39 inclusive are moved so as to connect the positive pole of source 47 to the line L and the polarized relays 21 and 102, the corresponding windings 25 to 29 inclusive are energized in addition to the movement of the cam shaft 70, while if the pole changers are not so moved, the cam shaft 70 is made to execute its step-by-step movement without the energization of the corresponding magnets 25 to 29 inclusive.

When the selecting mechanism is acting solely as a distributor of the effects of current impulses arriving from a distant station over line L, the operation is precisely as hereinabove described, except that the polarized relays 21 and 102 are operated by a sequence of current impulses flowing over line L instead of current from source 47, and the condition of line switch 46 remains un-

altered with movable contact 48 in engagement with fixed contact 49.

What is claimed is:

1. A selecting mechanism comprising a plurality of switches, cams for actuating said switches, an electromagnet, and step-by-step apparatus coöperating therewith and controlled by the cam-actuated switches for effecting the rotation of said cams.
- 10 2. A selecting mechanism comprising a plurality of sets of switches, current-polarity controlling means coöperating with one of said sets of switches, an electromechanism coöperating with another of said sets of switches, mechanism for simultaneously actuating switches from both sets, and an electromagnet controlled by the first of said sets of switches for operating said mechanism.
- 20 3. A selecting mechanism adapted for use as a current impulse transmitter and receiver comprising a plurality of sets of switches, impulse controlling circuit connections coöperating with said switches of one of the sets, electromechanism coöperating with said switches of another of the sets, a device for simultaneously operating a plurality of said switches, there being at least one switch from at least two sets and an electromagnet for operating said device.
- 25 4. A selecting mechanism for producing a succession of current impulses comprising a source of current, a plurality of switches coöperating therewith and adapted to be operated in succession, a plurality of cams for actuating said switches, an electromagnet and step-by-step apparatus coöperating therewith for rotating said cams a plurality

of steps to actuate said switches successively, and current controlling means coöperating with said switches and said source to vary the effect of the coöperation of said switches and said cams.

5. A selecting mechanism comprising a plurality of sets of switches, current controlling means coöperating with one of the sets to form a succession of current impulses, a selecting device coöperating with another of the sets to selectively control the performance of a plurality of functions, means for simultaneously closing switches of both sets, and an electromagnet for insuring the step-by-step operation of said switch closing means.

6. A selecting mechanism for producing a selective succession of current impulses and selectively performing a plurality of functions comprising in combination a current controlling means for determining the character of the impulses produced, selecting devices for controlling the function performed, a plurality of sets of switches, one set coöperating with said means and another with said devices, a switch actuator for closing both sets of switches, and an electromagnet for giving said actuator a step-by-step movement to invariably close said switches in the same order.

In witness whereof, I hereunto subscribe my name this 24th day of February A. D., 1915.

FRED R. McMURRY.
